Electric & Manufacturing Company, East Pitts-
burgh, Pa., a corporation of Pennsylvania

Application January 11, 1934, Serial No. 706,180

13 Claims. (Cl. 123—173)

Our invention relates to engines and it has for an object to provide improved means of support for the engine cylinder or cylinders.

A further object of our invention is to provide means for water-jacketing the engine cylinder and head structure.

A further object of our invention is to provide an engine frame embodying a member for supporting the cylinders and having openings therein which function as jacket spaces for the lower portions of the cylinders and which assure correct positioning of the latter.

A further object of our invention is to provide an improved engine frame including a horizontal member to which the cylinders are attached together with transverse frame elements connected to the bottom surface of the member and carrying the crank shaft bearings, the frame elements serving both as arches to support the engine as well as the tension or stress structures resisting engine working forces.

A further object of our invention is to provide an engine frame embodying a tabular support having sockets therein for positioning the cylinders together with tie rods for holding the cylinders in the sockets.

A further object of our invention is to provide an engine frame having a tabular support to which the cylinders are connected, the tabular support providing lower jacket spaces for the cylinders together with means providing upper jacket spaces for the cylinders communicating with the lower jacket spaces and with jacket spaces provided in the head constructions.

A further object of our invention is to provide a head construction for an engine cylinder embodying inner and outer covers, the inner cover having a fluid tight connection with respect to the upper end of the corresponding cylinder and the outer covers having limited compressive engagement with the top surfaces of the inner cover so as to provide jacket spaces between the covers.

A further object of our invention is to provide an engine cylinder construction embodying a head including an inner cover connected by a fluid-tight joint to the upper end of the cylinder and an outer cover having limited compressive engagement with respect to the top surface of the inner cover to provide a jacket space between the covers and the outer cover extending outwardly beyond the periphery of the inner cover to provide means of attachment of a jacket member providing a jacket space encompassing the upper portion of the cylinder and commu-

nicating with the jacket space provided between the inner and outer covers.

These and other objects are effected by our invention as will be apparent from the following specification and claims taken in connection with the accompanying drawings, forming a part of this application, in which:

Fig. 1 is a transverse sectional view of our improved engine;

Fig. 2 is a fragmentary view partly in plan and partly in section, the sections being at the levels of the lines I—I and II—II of Fig. 1;

Fig. 3 is a fragmentary detail view showing the top plate and the connection thereof to the frames; and

Fig. 4 is an enlarged detail view showing the relation of cylinder and top plate structure.

Referring to the drawings more in detail, we show an engine embodying a frame construction, at 9, for supporting a crank shaft 11 and cylinders 12, the frame construction being mounted on a suitable bed plate 10. The frame includes a horizontal member or tabular support 13 connected to transverse frames 14, the cylinders being attached to the tabular support and the crank shaft 11 and crank shaft bearings 15 being carried by the transverse frames.

The horizontal plate or tabular support 13 has openings 16 formed therein for the cylinders 12. As shown, each opening 16 preferably has 30 a shallow counterbore 17 at its upper end and preferably has an inwardly-extending flange 17' at its lower end, the counterbore and the flange providing cylindrical seating surfaces 18 and 19, respectively, and the counterbore having an abutment surface 20, said surfaces providing a cylinder socket.

The cylinders 12 are each formed with a central enlargement 21, preferably cylindrical, and with upper and lower portions 22 and 23, respectively, of smaller diameter. The central enlargement 21 is provided with a lower cylindrical seating surface 24 and with an abutment surface 25 fitting the counterbore cylindrical seating surface 18 and abutment surface 20, respectively, and the lower cylindrical portion 23 has an external cylindrical seating surface 26 which fits the cylindrical surface 19 provided by the flange 17'. Thus, it will be seen that the socket relation of the top plate and of the cylinders assures that the latter may be readily and properly positioned with respect to the frame.

Each cylinder rests on the tabular support 13 due to engagement of its enlargement abutment surface 25 with the bottom of the counterbore 17. 55

A circumferential series of vertical tie rods 27 have their lower ends anchored at 28 to the inwardly-extending flange 17', the tie rods extending upwardly through the main opening 16 5 and externally of the lower cylinder portion 23 and through openings 29 provided in the central enlargement 21, the upper ends of the rods passing through openings 30 provided in the cylinder head construction, at 31, and nuts 32 cooperate 10 with the upper ends of the rods so that, when the nuts are tightened, the cylinder 12 is held in place in its socket under compression.

The tabular support 13 not only serves to support the cylinders and to provide guiding sockets 15 for the latter to assure correct positioning of the cylinders, but the tabular support also provides water-jacket spaces for the lower portions 23 of the cylinders, such water-jacket spaces being constituted by the main openings 16 which 20 are of larger internal diameter than the external diameter of the cylinder portions 23, the main openings 16 being overlapped or covered at the top by the central enlargement 21 and being closed at the bottom by the sealing fit of the flanges 25 17' with respect to the annular seating faces 26, the annular seating faces preferably having sealing or packing rings 33 to make the joint between the lower cylinder portions 23 and the flanges 17' fluid-tight while at the same time 30 permitting of relative movement occurring incident to assembly or possibly to differential expansion of the parts due to temperature conditions.

The upper portions 22 of the cylinders are provided with the head constructions, at 31, already referred to. Preferably, each head construction embodies inner and outer covers 34 and 35, the inner cover having a liquid and gas-tight annular connection with respect to the upper end of the cylinder. As shown, each inner cover has a downwardly extending annular flange 36 provided with 40 an annular tenon portion 37 fitting an annular socket 38 provided in the upper end of the cylinder, whereby a lap joint is provided between the inner cover and the upper end of the cylinder, the lapping portion of the cover being exposed internally of the cylinder so that the annular joint will be of the smallest possible diameter, so that the area on which gas pressure acts is a minimum and so that the joint tends to tighten with increasing temperature. The outer cover 35 takes all the bending stresses due to gas loads on the inner cover, whereby the inner cover may be made relatively thin and flexible, of relatively small dimensions, and of a character promotive of good cooling.

Each outer cover 35 compressively engages the associated inner cover 34 to maintain the latter in position with respect to the cylinder, the compressive engagement preferably being limited to provide a jacket space between each pair of covers. For example, the limited compressive engagement is preferably afforded by downwardly extending lugs 39 formed on the outer cover 35 60 and engaging the top surface of the inner cover 34. Preferably, the lugs 39 are formed in circular series and have lower faces 40 machined to fit the top surface of the inner cover. To promote correct relative positioning of the inner and the outer covers, the inner cover has, for example, a cylindrical surface 41 encompassed by tongues 42 provided at the outer ends of the lugs 39. It will, therefore, be apparent that, due to the telescopic features of the joint formed 70 between each cylinder 12 and the inner cover 34

and between the inner and outer covers, it is assured that these elements may be readily and correctly positioned.

The outer cover 35 overlaps the outer periphery of the inner cover 34 to provide an annular portion 44 having said openings 30 for the tie rods 27. A downwardly-depending sleeve 45 is connected to the annular portion 44 and has a telescopic watertight joint, at 46, with respect to the upper portion of the central enlargement 21. Thus, it will be 10 seen that the tension rods 27 function to impose the necessary compressive engagement of the outer cover with respect to the inner cover as well as to hold the covers and the cylinder in place with respect to the top plate under compression.

Due to the limited compressive engagement between the inner and outer covers of each cylinder, a water-jacket space 47 is provided therebetween which communicates peripherally with 20 the upper water-jacket space 48 formed by the sleeve 45. The lower water-jacket spaces 49 provided by the openings 16 in the top plate 13 communicate with the upper jacket spaces through the passages 29 provided in the central enlargement 21 for the tie rods 27, the passages 29 being made sufficiently larger in size than the tie rods to afford adequate circulation. The lower jacket spaces 49 are connected by passages 49a to simplify the matter of water connections. 30

Where the engine is of the two-cycle type, the cylinders 12 are provided with any suitable arrangement of scavenged air admission ports 50 and exhaust ports 51, these ports extending through the central enlargement 21 and being disposed 35 above the member or tabular support 13 sufficiently to provide for a suitable air inlet manifold 52 and exhaust manifold 53 encompassing the central enlargement. The longitudinal passages 29, already referred to, formed in the central enlargement to afford communication between the upper and lower jacket spaces as well as to accommodate the tie rods 27 preferably extend through the bridging pieces formed between adjacent ports, whereby the port structure 45 may be adequately water-cooled.

A relatively rigid and strong frame is provided by the horizontal top plate or tabular support 13 and by the vertical transverse frames 14, the latter being connected to the tabular support 50 by screws 13'. Each of the frames is formed to provide a horizontal arch for supporting the engine and giving transverse stiffness thereto as well as to provide tension or stress structures 55 which cooperate with the tabular support and with the tension rods to resist engine working forces. To this end, we show each frame 14 cut from suitable plate steel in such a manner as to have the material disposed so as to act efficiently 60 in resisting the stresses encountered as well as in affording the requisite stiffness.

By way of example, we show each frame 14 including a top horizontal member 54, inclined side or brace members 55, vertical tension members 56, and lower arch members 57 and 58, the arch members 57 being joined at their outer ends to the lower ends of the brace members 55 and at their inner ends to the lower ends of the vertical tension members 56 and the member 58 having its ends joined to the lower ends of the vertical members 56 at the junction regions of the latter with the members 57; and the member 58 is curved to provide, with said junction regions, the upper half 59 of a crank shaft bearing 15, 75

the lower half 60 of such bearing being connected thereto in the usual way.

Thus, it will be seen that, as the top horizontal members 54 of the frames are connected to the tabular support 13 by suitable means, for example, the bolts or screws 13', as the tie rods 27 are connected to their lower ends to the tabular support 13 and at their upper ends to the head portions of the cylinders, and as the crank shaft bearings are carried by the frames 14, it will be apparent that adequate tension structure is interposed between the cylinder heads, at 31, and the crank shaft bearings to resist engine working forces.

15 Since the cylinders are relieved of tension forces, these being resisted by the tension rods 27, the construction is particularly useful with a two-cycle engine, for an engine of this type usually has the cylinders provided with scavenging ports which tend to weaken the cylinder structure and make it less capable of 20 withstanding working stresses. Furthermore, the frame portions 14 of the tension structure provided for resisting engine working forces are 25 formed as arches for supporting the engine as well as the crank shaft bearings. The members 55 of the frames 14 give lateral stiffness to the structure, the vertical tension members 56 largely 30 withstand tension forces tending to separate the crank shaft bearings and the cylinder heads, and the members 57 and 58 constituting arches or girders which carry the crank shaft bearings and are strengthened by the members 55 and 56, the members 57 and 58 also cooperating with 35 the members 55 and 56 to provide a relatively stiff frame construction. In other words, the material in each frame 14 is disposed so as to act efficiently in resisting all forces imposed thereon. The frames 14 are connected to foot 40 constructions 62, which, in turn, are connected to a bed plate 10 in the usual way. The side plates 63 are welded to the side members 55 of the cross frames and contribute to stiffness of the structure. Longitudinal members 63a are attached to each cross frame and give rigidity to 45 the structure resisting forces acting horizontally of the bearings. Thus it will be seen that the side plates 63 and the longitudinal members 63a cooperate to keep the frames, particularly the 50 lower portions thereof in proper locations.

Since the tabular support or member 13 is detachably connected to the cross frames 14, the side plates 63 cannot be welded to the member 13 to provide for an oil tight connection with respect to the latter. Therefore, a top plate 13a, arranged below the tabular support, is welded to the side plates 63 to give the requisite oil tightness.

As each head construction, at 31, is composed 60 of inner and outer covers separated by jacket spaces, we prefer to have the fuel injection atomizer 64 attached only to the inner cover 34, as indicated at 65, and having a sliding joint, as shown at 66, with respect to the outer cover 38, 65 whereby any link or strut effect of the atomizer between the covers is avoided and relative movements of the covers may take place without interference by the atomizer. This feature of construction is disclosed and claimed in the application of E. S. Dennison, Serial No. 698,187, filed November 15, 1933.

From the foregoing, it will be apparent that we have devised an engine whose component parts are constructed and arranged, not only 75 of simple design permitting of ready manufac-

ture, but so that they fit together readily in correct relative positions, and one wherein the cylinders and heads are effectively cooled, the cooling means being embodied also as a part of the means for supporting the cylinders. The tie rods 5 for connecting the cylinders to the tabular support are arranged in the water jacket spaces in order to locate such rods as close as possible to the cylinder axis to minimize the required size and mass of the head construction. Furthermore, we isolate and resist engine working forces so far as the cylinders and the frame are concerned, the tension rods 27, the portions of the top plate joining the tension rods and the transverse frame members, and the transverse frames, 10 constituting stress constructions for withstanding engine working forces. In addition, the transverse frame members are formed to provide arch constructions both for the purpose of supporting the engine and for giving transverse stiffness 15 thereto in all directions.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are imposed by the prior art or as are specifically set forth in the appended claims.

30 We claim:

1. In an engine, a support having an opening and provided with an inwardly-extending flange at the lower end of the opening, a cylinder having an intermediate enlargement resting on top 35 of said support and having a lower portion depending through said opening, said enlargement having an annular series of longitudinal passages formed therein, a head construction for the cylinder, tension rods anchored to said flange and 40 extending upwardly through the opening and between the lower portion of the cylinder and the support and through said enlargement passages, and means abutting the head construction and cooperating with the upper ends of the 45 rods to place the latter under tension so that the portion of the head construction and of the cylinder intervening between said means and the top of the support are held together and in place 50 with respect to the support under compression. 50

2. In an engine, a support having an opening, a cylinder having an intermediate enlargement overlapping the opening and resting on the support; said cylinder having upper and lower portions of smaller external diameter than the 55 enlargement and the lower portion depending through the support opening; means providing a fluid-tight telescopic joint between the lower portion of the support and the exterior of the lower portion of the cylinder and the latter being 60 smaller than the portion of the opening above the joint so that the opening wall defines a lower jacket space for said cylinder; tension means for connecting the cylinder to the support; a cover for the cylinder; and means for jacketing 65 the cylinder including said lower jacket space, a sleeve carried by the head and telescoping the enlargement to provide an upper jacket space and longitudinal passages formed in the enlargement to afford communication between the 70 upper and the lower jacket spaces.

3. In an engine, a support having an opening and a flange at the lower end of the opening; a cylinder having a central enlargement overlapping the upper end of the opening; said cylin- 75

- der having upper and lower portions of smaller external diameter than the enlargement and the lower portion extending through said opening and fitting the flange; the wall of the portion 5 of the opening above the flange being spaced from the lower cylinder portion to define a lower jacket space for the cylinder; a head for the cylinder; a sleeve connected to the head and telescoping the enlargement to provide an upper 10 jacket space for the cylinder; said enlargement having a circumferential series of longitudinal passages affording communication between the upper and the lower jacket spaces; and a circumferential series of tension rods attached to the flange at their lower ends, extending through the 15 lower jacket space and the longitudinal passages, disposed in the upper jacket space, and having their upper ends connected to the head to hold the latter and the cylinder in place with 20 respect to the support, the portions of said rods disposed in the longitudinal passages being smaller than the latter to provide for flow around the rods.
4. In an engine, a support having an opening, a counterbore at the upper end of the opening and having a flange at the lower end of the opening; said counterbore and said flange being provided with coaxial cylindrical seating surfaces; a cylinder having a central enlargement 25 overlapping the upper end of the opening; said cylinder having upper and lower portions of smaller external diameter than the enlargement and the enlargement and the lower portion having coaxial cylindrical seating surfaces fitting the cylindrical seating surfaces of the counterbore and of the flange; the wall of the opening above the flange defining a jacket space for the cylinder; a head for the cylinder; a sleeve connected to the head and telescoping the enlargement to provide an upper jacket space for the cylinder; said enlargement having a circumferential series of longitudinal passages affording 30 communication between the upper and the lower jacket spaces; and a circumferential series of tension rods attached to the flange, extending upwardly through the lower jacket space and the longitudinal passages, disposed in the upper jacket space, and having their upper ends attached to the head to hold the latter and the cylinder in place with respect to the support; the portions of said rods disposed in the longitudinal 35 passages being smaller than the latter to provide for flow around the rods.
5. In an engine, a support having an opening and an inwardly-extending flange at the lower end of the opening, a cylinder having an intermediate enlargement overlapping the opening and resting on the support, said cylinder having upper and lower portions of smaller external diameter than the enlargement and the lower portion depending through said opening and fitting within the flange, the wall of said opening above the flange being spaced from the cylinder to define a lower jacket space for the latter, a cover for the upper end of the cylinder; said cover having a portion extending outwardly of the upper portion of the latter, said cover having a jacket space, a sleeve connected to the cover and telescoping the enlargement to provide an upper jacket space for the cylinder communicating with the jacket space of the cover, said enlargement having longitudinal openings 40 provided therein to afford communication between the upper and the lower jacket spaces, and tension 45 rods means for connecting the cover to the support to

maintain the cylinder in proper relation with respect to the latter.

6. In an engine, a support having an opening and an inwardly-extending flange at the lower end of the opening; a cylinder having an intermediate enlargement overlapping the upper end of the opening and resting on the support; said cylinder having upper and lower portions of smaller external diameter than the enlargement and the lower portion depending through said opening and having a fluid-tight seal with respect to the flange; the wall of said opening above the flange being spaced from the cylinder to define a lower jacket space for the latter; a cover for the upper end of the cylinder; said cover extending outwardly beyond the periphery of the upper portion of the cylinder and having a jacket space; a sleeve connected to the cover and telescoping the enlargement to provide an upper jacket space in communication with the cover jacket space; said enlargement having longitudinal openings to provide communication between the upper and the lower jacket spaces; and tension rods having their lower ends anchored to said flange and extending upwardly through the lower jacket space, the longitudinal openings, and the upper jacket space and having their upper ends connected to the cover, the portions of said rods disposed in said longitudinal 50 openings being sufficiently smaller than the latter to provide for circulation of cooling medium through said openings.

7. In an engine, a support having an opening, a counterbore at the upper end of the opening and an inwardly-extending flange at the lower end of the opening; a cylinder having an intermediate cylindrical enlargement provided with ports separated by bridging pieces and having its lower end fitting said counterbore; said cylinder having upper and lower portions of smaller diameter than the enlargement and the lower portion depending through said opening and having a sealed connection with respect to the flange; the wall of said opening above the flange being spaced from the lower cylinder portion to define a lower jacket space for the latter; a cover for the upper end of the cylinder; said cover having a portion extending outwardly from the cylinder and having a jacket space; a sleeve connected to the outwardly-extending portion of the cover and telescoping with said enlargement to provide an upper jacket space for the cylinder communicating with the cover jacket space; said enlargement having a circumferential series of longitudinal openings passing through the bridging pieces and affording communication between the upper and lower jacket spaces; an annular series of tension rods anchored at their lower ends to said flange and extending upwardly through the lower jacket space, said longitudinal openings, the upper jacket space, and openings formed in said cover; and means cooperating with the upper ends of said rods and abutting the upper surface of said cover to place the intervening structure under compression, the portions of said rods extending through said longitudinal openings being sufficiently smaller in cross-sectional area than the latter so that the openings afford adequate circulation between the upper and lower jacket spaces.

8. In an engine, a support having an opening, a cylinder having an intermediate enlargement overlapping the opening and resting on the support, said cylinder having upper and lower portions of smaller diameter than the enlargement

- and the lower portion depending through the support opening, said opening, for the major portion of the depth thereof, being larger than the lower portion of the cylinder to provide a 5 jacket wall spaced from the latter, means providing a fluid-tight connection between the support and the lower cylinder portion at the lower end of said opening so that said jacket wall defines a lower jacket space for the cylinder, a head for the cylinder, tension means for connecting the head to the support to hold the cylinder in place with respect to the latter, said enlargement having ports extending therethrough above the support and the ports being separated by bridging pieces, and a sleeve carried by the head and telescoping said upper portion of the enlargement to provide an upper jacket space, said enlargement having longitudinal openings passing through the bridging pieces to provide for communication between the upper and lower jacket spaces.
9. In an engine, a support having an opening, a cylinder having an intermediate enlargement overlapping the opening and resting on the support, said cylinder having upper and lower portions of smaller diameter than the enlargement and the lower portion depending through the support opening; said support opening being of larger internal diameter than the external diameter of the lower portion of the cylinder, means 25 providing an annular sealed joint between the exterior of the lower portion of said cylinder and the lower portion of said support, whereby the latter functions to provide a lower jacket space for the cylinder, said enlargement including a plurality of bridging pieces with ports therebetween, a head structure for the cylinder, means cooperating with the cylinder to provide an upper cooling jacket space for the latter, said intermediate enlargement having longitudinal openings 30 formed therein and passing through the bridging pieces to afford communication between the upper and lower jacket spaces, and tension rods extending through the upper and lower jacket spaces and said longitudinal openings and connected at their upper and lower ends to the cylinder head structure and to said support, respectively, at least the portions of said rods disposed in the longitudinal openings being of smaller diameter than the latter.
10. In an engine, a support; a cylinder having an enlargement extending for a portion of its length; means cooperating with the cylinder above and below the enlargement to provide cooling jacket spaces for the cylinder; said enlargement having longitudinal passages provided therein to afford communication between the cooling jacket spaces; and means including tension rods extending through said passages for holding the cylinder in place with respect to the support.
11. In an engine, a tabular support having an opening, a flange at the lower end of the opening, and a counterbore at the upper end of the opening; said counterbore and said flange having coaxial cylindrical seating surfaces; a cylinder having an intermediate enlargement and a smaller lower portion and the enlargement having longitudinal passages formed therein; said enlargement fitting the counterbore and the lower portion of the cylinder depending through the opening and fitting the cylindrical seating surface of the flange; the wall of said opening defining a jacket space encompassing the cylinder between the enlargement and the flange; and means for connecting the cylinder to the support including a circular series of tension rods connected at one end to the flange, extending through the upper portion of said opening and 10 extending through the passages formed in said enlargement.
12. In an engine, a tabular support having an opening and an inwardly-extending flange at the lower end of the opening, a cylinder provided 15 with an intermediate enlargement resting on the top side of said support, said cylinder having upper and lower portions of smaller diameter than the enlargement extending upwardly and downwardly, respectively, from the enlargement 20 and the lower portion extending through the opening and telescoping with respect to the flange to provide a fluid-tight joint, the opening above the flange being larger than the lower cylinder portion to provide a jacket space for the latter, 25 a cover construction for the upper end of the cylinder and having an annular portion extending outwardly from the cylinder, tension rods anchored at their lower ends to said flange and extending upwardly through said jacket space 30 and through openings provided in said enlargement and in said annular portion, and nuts abutting the top side of the cover construction and cooperating with the upper ends of the tension rods to place the latter in tension so as to hold 35 the cylinder and the cover construction compressively in place with respect to the support.
13. In an engine, a support having an opening and an inwardly-extending flange at the lower end of the opening, said opening being counterbored at its upper end; said counterbore and the flange having coaxial cylindrical seating surfaces; a cylinder provided with an intermediate enlargement having a cylindrical seating surface fitting said counterbore seating surface; said cylinder having upper and lower portions of 40 smaller external diameter than the enlargement and the lower portion depending through the support opening and having a cylindrical seating surface coaxial with the enlargement cylindrical surface and fitting said flange seating surface; the portion of said opening above the flange being larger than the lower portion of the cylinder so that the wall of such opening portion defines a lower jacket space for the cylinder; 45 a head for the cylinder; tension means for connecting the head to the support; and means for jacketing the cylinder including said lower jacket space, a sleeve carried by the head and arranged in telescopic relation with respect to the upper 50 end of said enlargement to provide an upper jacket space, and longitudinal openings formed in said enlargement to afford communication between the upper and lower jacket spaces.
